United States Patent Office

Des. 178,956
Patented Oct. 16, 1956

178,956

DINNER PLATE OR SIMILAR ARTICLE

Richard H. Garvin, Syracuse, N. Y., assignor to Onondaga
Pottery Company, Syracuse, N. Y., a corporation of
New York

Application April 23, 1954, Serial No. 30,148

Term of patent 14 years

(Cl. D44—15)

The drawing is a plan view of a dinner plate of conventional configuration showing my new design.

I claim:

The ornamental design for a dinner plate or similar article, as shown and described.
